MATERIAL FEEDING APPARATUS
Walter P. Niblick, Sr., 8803 S. Main, Houston, Tex.
Filed Sept. 30, 1965, Ser. No. 491,722
9 Claims. (Cl. 198—220)

The present invention relates to a material feeding apparatus, and more particularly, relates to various improvements in an oscillatory feeder.

Material feeders are employed in many processing systems for transporting material from one processing station to another and for feeding material at a uniform or regulated feed control rate. The present invention is generally directed to various improvements in an oscillatory material feeder.

It is the general object of the present invention to provide a material feeder, for example only such as for pecans, cherries, corn, coffee beans by which the material may be moved from one processing station to another such a grader, sorter, or packages at a regulated or uniform feed control flow.

A still further object of the present invention is the provision of an oscillatory feeder which has overcome the usual bearing problems for an oscillating shaft by providing shockmount bearings for supporting the oscillating shaft which will absorb any radial or transverse shock of the oscillating shaft.

Still a further object of the present invention is the provision of an oscillatory feeder wherein the oscillating shaft is surrounded by an overrunning clutch encircled by a sleeve which is in turn inserted into a larger overrunning clutch, the two clutches being rotatable in opposite directions so that when the shaft is oscillated the sleeve is rotated in one direction to provide even wear in the bearing support.

Yet a further object of the present invention is the provision of an oscillatory material feeder in which the vibrating electric motor includes an electromagnet having a core and a pole piece secured to the shaft to be oscillated, an armature which is supported from the electromagnet by a pair of leaf springs which provide increased stability and which may include adjusting means for adjusting the gap between the pole piece and the armature to vary the power output of the motor without varying the frequency of operation.

A still further object of the present invention is the provision of an oscillatory feeder which is provided with a tray having a bottom directed horizontally downwardly but at an angle less than that at which self feeding would occur.

Still a further object of the invention is the provision of an oscillatory material feeder tray having a lip adjacent the discharge side of the tray which projects outwardly and upwardly to retard self feeding and which includes a notch extending towards the bottom of the tray to provide self cleaning of the tray.

Yet a further object of the present invention is the provision of an oscillatory feeder having an adjustable support for the feeder tray for balancing the centrifugal forces on the feeder as it is oscillated.

A still further object of the present invention is the provision of a material feeding tray having an upwardly projecting rib on the bottom of the tray surface to increase the feeding movement, particularly for sticky products.

Yet a further object of the present invention is the provision of an oscillatory material feeding apparatus having a tray in which the bottom is directed at an angle downwardly, a vertical wall connected to the outer periphery of the tray bottom and including a material discharge opening adjacent to lower side of the bottom, the vertical

2

wall forming a rounded interior connected to the bottom for ease in cleaning, a lip projecting outwardly and upwardly from the bottom adjacent the discharge opening, the lip including a notch at the lowest point on the lip and extending to the bottom for self cleaning of the bottom, and means connected to the bottom for oscillating the bottom thereby feeding a material from the discharge opening.

Other and further objects, features and advantages 10 will be apparent from the following description of a presently preferred embodiment of the apparatus of the present invention given for the purposes of illustration and taken into conjunction with the accompanying drawings, where like character references designate like parts 15 through the several views, and where:

FIGURE 1 is a perspective view of the apparatus of the present invention,

FIGURE 2 is an enlarged cross-sectional view of the feeder tray of the present invention,

FIGURE 3 is an enlarged top elevational view of the feeder tray,

FIGURE 4 is an enlarged cross-sectional view of the present invention,

FIGURE 5 is a perspective view of the vibratory electric motor of the present invention,

FIGURE 6 is an enlarged fragmentary cross-sectional view of a modified type of bearing support, and

FIGURE 7 is a fragmentary view of the armature support and adjustment of the present invention.

Referring now to the drawings, particularly FIGURES 1 and 4, the reference numeral 10 generally indicates the oscillatory feeder of the present invention and generally includes a feeder tray 12 and suitable motor means 14 for supplying an oscillating movement to the tray 12. The apparatus 10 is suitable for placement in any material processing system for receiving incoming material which is to be transported and fed at a regulated flow control to another portion of the process such as in a grader, sorter, or packager.

While any suitable feeder tray 12 may be used, preferably, the feed tray 12 generally includes a bottom 16, a sidewall 18 and a projecting lip 20. The bottom is directed at an angle directed downwardly, for instance, in the range of three degrees to twelve degrees depending upon the material to be fed. That is, a smaller deviation from the horizontal, for example, three degrees, provides a lower rate of feeding for a fixed diameter size of the bottom 16. Of course, the feeding rate can be increased by either increasing the diameter of the bottom 16 or increasing the deviation angle of the bottom downwardly from horizontal. And, of course, the deviation from horizontal will be increased in the material being fed is sticky. However, the downward tilt of the bottom 16 should not be so great as to cause self feeding from the feed tray 12 which would occur even without oscillation of the tray 12 at too large deviation angles.

The vertical sidewall 18 is connected about the outer periphery of the bottom 16 and includes a discharge opening 22 adjacent to the lowest edge of the bottom 16 for providing a discharge opening. Preferably, the vertical wall 18 is connected to the bottom 16 by a rounded interior corner 24 so that the feed tray 12 may be easily and thoroughly cleaned which is an important requisite in handling food products.

Referring now to FIGURE 2 and 3 the lip 20 includes a notch 26 in the lower part of the lip and extending to the bottom 16 so that the feeding tray 12 will be self cleaning. That is, as the tray 12 is oscillated it can be emptied of material which will normally flow outwardly and downwardly toward the lowest portion of the bottom 16 and the lip 20. While the lip 20 performs the function of re-

tarding self-feeding of the apparatus 10 such as might be caused by external vibrations, which are frequently present in processing operations, the notch 26 which extends to the bottom will allow removal of all of the material in the tray 12 as it is fed downwardly towards the notch 26.

If desired, a rib 28 may be provided extending approximately from the center of the bottom 16 and radially outward towards the top of the bottom 16. The length of the rib 28 is sized so that the rib will fit on the interior of a feeding tube 30, shown in dotted outline, which normally supplies the input feed to the feed tray 12. Preferably, the rib 28 has concave sides 32 so as to direct the incoming feed out to the outer periphery of the bottom 16 and away from the center of the bottom 16 as the greatest oscillatory movement and consequently the material feed from the tray 12 is around the sides of the bottom 16. Of course, the rib 28 may be omitted if desired.

As can best be seen from FIGURE 2, the cross-section area of the feeder tray 12 is not symmetrical and therefore it is preferable to provide a suitable adjustable support for balancing the tray 12 as it is oscillated on a shaft 34 from the motor means 14. Thus, a suitable adjustable support 36 may be provided having a notch 38 therein which is generally horizontally directed so that the shaft 34 may be connected to the support 36 by a suitable nut 40 at the centrifugal center of gravity of the tray 12 to balance the centrifugal forces on the feed tray 12. Also, if an extension is added to the lip in use the tray can be easily balanced by the adjustable support to compensate for the nonsymmetrical forces which may be added.

While any suitable motor means 14 may be utilized for providing an oscillating movement at the desired frequency to the tray 12, it is preferable to use a vibratory motor such as described in my Patent No. 2,859,362 but including several improvements thereto. Thus, referring now to FIGURES 4 and 5, the motor means 14 generally includes a frame 40 for providing a support for the oscillating shaft 34 at opposite ends. As an oscillating shaft is the most difficult type of movement to provide satisfactory bearings for, one feature of the present invention is the provision of resilient shockmounts which are secured to the shaft 34 at opposite ends and supported by the frame 40. The shockmounts 42 may be secured to the shaft 34 by any suitable means such as pins 44. Thus, a shockmount, such as manufactured by Lord, will absorb the radial and transverse shock to the oscillation of the shaft 34 and the loading of the tray 12.

Electromagnet core 50 is provided having a coil 52 wound thereon. An armature 54 is supported from the electromagnet by a pair of leaf springs, preferably fiber-glass Scotch-ply springs 56. Thus, when the coil 52 is energized by an alternating current the armature 54 is alternately attracted and released by the pole pieces of the core 50. The entire electromagnet and armature structure is secured to the shaft 34 so that the shaft 34 is subjected to the oscillatory movement when the electromagnet is energized. Preferably, the shaft 34 is secured by a press fit into a bore 60 of the electromagnet and armature assembly at a nodal point so that the only movement transmitted to the shaft 34 is radial oscillatory movement and the electromagnet and armature structure may be supported from the shaft 34. Referring to FIGURE 7, it was noted that the armature 54 was supported by a pair of leaf springs at opposite sides of the armature and electromagnet core. The use of two springs provides stability by keeping the armature 54 aligned with the poles of the core 50 and preventing it from whipping sideways. Furthermore, the springs may easily be replaced with different sized springs to change the frequency of operation. In addition, a bracket 62 connected to the leaf springs 56 includes suitable adjusting means for adjusting the gap between the pole and the armature 54. Thus, openings 64 may be provided in the bracket 62 which are

sized larger than the bolts 66 which secure the armature 54 to the bracket 62 so that the armature 54 may be adjustably secured to the bracket 62 to vary the gap 68 between the armature and the pole pieces of the magnetic core 50 for suitably adjusting the power output and operation of the electric motor means.

In some applications it is desirable to maintain the radial center of the oscillating shaft 34 by securely mounting the oscillating shaft firmly in rigid bearings. Normally, however, standard bearings have a short life when used with an oscillating shaft. Referring now to FIGURE 6 the shaft 34 is shown supported at either end by a clutch and bearing assembly providing even wear in the bearing support. Thus, a first overrunning clutch 70 encircles the shaft 34, preferably a clutch and bearing assembly such as manufactured by Torrington, type DC, a sleeve 72 is secured to the outer surface of the first overrunning clutch 70, and a second overrunning clutch assembly 74 is provided encircling the sleeve 72, all of which is suitably supported from the frame 40. The two overrunning clutches 70 and 74 are arranged to rotate in opposite directions and since the sleeve 72 is pressed over the smaller overrunning clutch 70 through which the oscillating shaft 34 oscillates, it is evident as long as the shaft 34 oscillates there will be constant rotation of the sleeve 72 in one direction. This action will prevent what is known as birolling in standard roller bearings on oscillatory shafts. That is, the sleeve 72 will be forced to rotate thereby providing even wear in the support mechanism. For example, assuming that the shaft 34 oscillates and the overrunning clutch 70 engages when the shaft rotates counterclockwise, the clutch 70 and the sleeve 72 will also rotate counterclockwise. Since, however, the second overrunning clutch 74 rotates in a clockwise direction and is generally stationarily supported by the frame 40 it will allow the overrunning clutch 70 and the sleeve 42 to rotate in a counterclockwise direction but not in a clockwise direction on each oscillation of the shaft 34 in a counterclockwise direction thereby continually rotating the inner clutch 70 and the sleeve 72 in a counterclockwise direction to provide even wear on the bearing assembly.

In addition, the bearing is suitably held in place such as by providing a lip 80 on one side of the bearing assembly, and a washer 82, which is held in place by a snap ring 84. Since the lower bearing assembly 69 is similarly supported the shaft 34 will be securely supported for both vertical and oscillating movement.

In operation, the motor means 14 is suitably actuated by controls which are conventional and which form no part of the present invention to oscillate the feed tray 12 about the shaft 34 to provide the desired flow rate. The adjusting means 36 is adjusted to balance the centrifugal forces acting on the tray 12 as it oscillates.

Material is suitably fed to the feed tray 12, such as by incoming feed tube 30, which does not form part of the present invention, or is otherwise deposited in the feed tray adjacent the upper end of the bottom 16. The oscillating movement of the tray 12 throws the material towards the outer periphery of the bottom 16 on each side of the tray and down the bottom towards the discharge opening 22. The lip 20 will normally hold material in the tray 12 and prevent self feeding and feeding due to external vibration. However, the oscillating movement of the tray 12 will cause the material to flow to the lowermost portion of the bottom 16 and over the lip 20. The rate of oscillation is regulated by the motor means and suitable controls to provide a uniform or regulated speed control flow out of the tray 12. And the rib 28 will move the incoming material to the outer edge of the bottom 12 where the oscillating motion is greatest and is particularly useful with sticky products to insure a uniform flow rate out of the feed tray 12.

At the end of a product run the tray may continue to vibrate and flow the remaining fluid downwardly adjacent the edge of the lowermost part of the edge of the lip 20

towards the notch 26 and out of the tray so that the tray will clean itself. And of course, when it is necessary to manually clean the tray the rounded corners 24 between the vertical wall 18 and the bottom 16 may be easily cleaned to prevent any build-up of deposits in sharp corners of products which would be deleterious to food.

And of course, in the motor means 14, the armature 54 may be suitably adjusted by its connection to the bracket 62 to adjust their air gap 68 to provide the desired amount of power output from the electromagnet and armature assembly and the double leaf springs 56 will advantageously provide a stability of operation and movement as the armature is attracted to and released from the electromagnetic poles of the core 50. It is noted that this method of power adjustment does not change the frequency of operation. And of course, the shockmounts 42, shown in FIGURE 4, will securely hold and absorb any radial and transverse shock without being subject to failure as ordinary bearings. And for a more positive radial stability of the oscillating shaft 34, when desired, the double and opposed overrunning clutch assembly of FIGURE 6 may be utilized which will securely hold and will evenly distribute the wear in the bearing assembly to provide an extremely long life structure.

The present invention, therefore, is well adapted to carry out the objects and attain the ends and advantages mentioned as well as other inherent therein. While a presently preferred embodiment of the invention is given for the purpose of disclosure, numerous changes in the details of construction, and arrangement of parts can be made which will readily adjust themselves to those skilled in the art and which are encompassed within the spirit of the invention and the scope of the appended claims.

What is claimed is:

1. A material feeding apparatus comprising:
a bottom directed at an angle downwardly,
a wall connected to the periphery of the bottom and including a material discharge opening adjacent the lowest side of the bottom, said wall forming a rounded interior connection to the bottom for cleaning,
a lip projecting outwardly and upwardly from the bottom adjacent the discharge opening,
said lip including a notch at the lowest point on the lip, said notch extending to the bottom for self cleaning of said bottom, and
means connected to the bottom for oscillating said bottom for feeding a material from the discharge opening.
2. The apparatus of claim 1 wherein said oscillating means is adjustably connected in a horizontal plane for balancing the centrifugal forces on the apparatus.
3. The apparatus of claim 1 including:
a rib extending radially from adjacent the center of the bottom outwardly towards but spaced from said wall.
4. The apparatus of claim 1 wherein the bottom is directed downwardly at an angle in the range of three to twelve degrees.
5. The apparatus of claim 3 wherein said rib includes sides concave shaped in cross section.

6. The apparatus of claim 1 wherein said means for oscillating said bottom includes:
a frame,
a shaft,
a bearing support at each end of said shaft including, a first overrunning clutch surrounding said shaft, a sleeve surrounding and secured to the exterior of said first clutch,
a second overrunning clutch encircling said sleeve, said overrunning clutches adapted to rotate in opposite directions when the shaft is oscillated whereby the sleeve is rotated in one direction to provide even wear in said support,
an electromagnet including a core and pole secured to said shaft,
an armature resiliently supported from said electromagnet whereby energization of said electromagnet will oscillate said shaft.

7. The apparatus of claim 1 wherein said means for oscillating said bottom includes:
a frame,
a vertical shaft,
a resilient shockmount bushing secured to each end of said shaft and supported from the frame, said shockmount bushings resiliently supporting the shaft both vertically and oscillatory movement,
an electromagnet including a core and pole secured to shaft,
an armature,
two leaf springs connected between the electromagnet and said armature for supporting said armature adjacent said pole, and
adjusting means carried by the springs for adjusting the gap between the pole piece and said armature.

8. The improvement in an oscillatory feeder pan comprising:
a bottom directed at an angle downwardly,
a vertically directed wall connected to the periphery of the bottom and including a material discharge opening adjacent the lowest edge of the bottom,
a lip projecting outwardly and upwardly from the bottom at the discharge opening,
said lip including a notch at the lowest point on the lip, said notch extending to the bottom for self cleaning of the bottom.

9. The apparatus of claim 8 including:
support means connected to said bottom, said support means being adjustably connected to the bottom in a horizontal direction for balancing the centrifugal forces on the pan when it is oscillated.
